[57] CLAIM

The ornamental design for a combined lotto ticket holder and checker, as shown and described.

DESCRIPTION

FIG. 1 is a front perspective of a combined lotto ticket holder and checker, showing our new design;

FIG. 2 is a front elevational view thereof;

FIG. 3 is a left end elevational view thereof;

FIG. 4 is a right end elevational view thereof;

FIG. 5 is a rear elevational view thereof;

FIG. 6 is a top plan view thereof;

FIG. 7 is a bottom plan view thereof; and,

FIG. 8 is an enlarged sectional view thereof taken on the line 8—8 of FIG. 2.
